UNITED STATES PATENT OFFICE.

HENRY ELSWORTH LOCK, OF ASSUMPTION, ILLINOIS.

BUTTER, LARD, AND CHEESE CUTTER.

1,079,135.

Specification of Letters Patent.

Patented Nov. 18, 1913.

Application filed May 14, 1913. Serial No. 767,534.

To all whom it may concern:

Be it known that I, HENRY E. LOCK, a citizen of the United States, residing at Assumption, in the county of Christian and State of Illinois, have invented certain new and useful Improvements in Butter, Lard, and Cheese Cutters, of which the following is a specification.

My invention relates to improvements in butter, lard and cheese cutters, although the improvement may be used for other purposes where it would perform its functions in a practical manner.

The main object of my invention is the provision of a device which can be easily operated to cut the material into separate or individual blocks of a determined size, shape, and weight, enabling the exact amount of material to be produced for any desired purpose.

Another object of my invention is the provision of a device of the character and for the purpose stated which will be of the simplest and cheapest possible construction, which will be easy to manipulate and be thoroughly efficient and which for the purpose intended will be entirely practical.

With these objects in view my invention consists of a device for the purpose stated embodying novel features of construction and combination of parts substantially as disclosed herein.

Figure 1 represents a perspective view of my complete device, and Fig. 2 represents a top plan view with a portion of the pressing arm and frame which provides the trough being removed, to show the arrangement and location of the cutting means.

My device is of extremely simple construction consisting of the base board A, which is provided with an opening B, to receive the cutting means C, which consists of a series of strips arranged to form pockets D, and the strips are formed with extended portions F, which are engaged by the pair of securing rods G, which retains the cutting device in place in the opening of the board. Upon the base board is secured the transverse strip H, to which by means of hinges J, is connected the pressing board K, formed

with a handle or grasping portion L, and this pressing board fits between the pair of longitudinal strips M, which form a chamber or trough N, upon the base board.

From the foregoing description the manner of using my invention will be readily understood, and I would state that the butter, lard, cheese, or other material to be cut is placed in the trough or chamber between the strips and upon the open cutting frame, 60 and in this position the hand operated pressing arm is depressed which action forces the material upon the cutting frame from which it is forced and deposits the material in individual blocks or pieces of a certain size, 65 weight, and shape.

It will thus be seen that I provide a device which costs very little and produces a handy article for the store or household as the size and shape of the block can be regulated to suit the circumstances, also the cutting frame can be easily applied and removed, also the device can be easily operated to produce the desired result, also the cutting frame can be made to produce blocks 75 of different shapes and that generally from every point of view the improvement is thoroughly efficient and practical.

The important feature of this invention is the construction of the pair of longitudinal strips and the connecting transverse strip which forms a trough to receive the material; the hinging of the pressing board to the transverse strip, and the cutting frame with extensions to be engaged by the rods, 85 all of which features are novel. The cutting frame with rods allows the frame to be inserted and removed with ease for cleaning and also permits of cutting frames of various shapes and sizes of pockets to be 90 used, which is very desirable.

I claim:

The butter, lard or cheese cutter herein shown and described, consisting of a base board provided with an opening, a cutting 95 frame fitting in said opening and having extensions engaging the walls of said opening to dispose the frame entirely within the opening, rods passing through the base board and the extensions of the frame to se- 100

cure the frame and permit its removal, a pair of longitudinal strips and a transverse connecting strip secured to the base board and forming a trough, and a presser board 5 hinged to said transverse strip and operating in the trough to force the material through said cutting frame.

In testimony whereof I affix my signature in presence of two witnesses.

HENRY ELSWORTH LOCK.
